UNITED STATES PATENT OFFICE

156,858

LIGHT MEASURING INSTRUMENT HOUSING

Willard Warren, Brooklyn, N. Y., assignor to
Joseph Warren, Long Island City, N. Y.

Application February 9, 1948, Serial No. 144,382

Term of patent 14 years

(Cl. D52—1)

To all whom it may concern:

Be it known that I, Willard Warren, a citizen of the United States, residing at Brooklyn, county of Kings, and State of New York, have invented a new, original, and ornamental Design for a Light Measuring Instrument Housing, of which the following is a specification, reference being had to the accompanying drawing, forming part thereof.

This application is a continuation-in-part of application Ser. No. D. 130,440, filed June 6, 1946.

Fig. 1 is a front perspective view of a light measuring instrument housing, showing my new design, and,

Fig. 2 is a rear perspective view of the same.

The coils shown in full lines in the band are repeated throughout the broken line area.

I claim:

The ornamental design for a light measuring instrument housing, as shown and described.

WILLARD WARREN.
